SUBSCRIBER'S CALLING DEVICE IN ELECTROACOUSTIC TRANSMISSION APPARATUS

Otto Tschumi, Soleure, Switzerland, assignor to Autophon Aktiengesellschaft, Soleure, Switzerland, a joint-stock company of Switzerland

Application May 12, 1944, Serial No. 535,294
In Switzerland November 6, 1942

6 Claims. (Cl. 179—81)

The invention relates to subscribers' calling devices in electro-acoustic transmission apparatus. In apparatus of this kind, calling takes place either by direct speaking or by a special audio frequency calling signal. However, in both cases, the person calling after the call and the change of the speaking direction, can hear things going on in the room of the person calling if there are not signalling bells independent of the actual transmission apparatus.

The subscriber's calling device according to the invention remedies these inconveniences. It is characterised by the fact that in the subscriber's station means are provided allowing the speaking signals to be locked at will in one or both speaking directions.

The accompanying drawing illustrates, by way of example, one embodiment of the invention.

Fig. 1 shows in a diagrammatic way the subscriber's device and

Fig. 2 a scheme of the repeater connected to the exchange of the subscriber's device.

Referring now to Fig. 1, EW designates an electro-acoustic transformer which may be used both as transmitter and as receiver. In the working moment shown in the drawing it is connected with the input transformer ET of the amplifier V through the switch u_1 , while the output transformer AT is in connection with the repeater LU through the switch u_2 and the contact SH₁. On the side of the line this repeater is earthed in the middle (at M₁). The free ends are connected with the outlet terminals a_2 and b_2 , the contact SH₂ with the terminals 1 and 2, bridged over by the condenser c, being interconnected in the one branch (b_2).

Referring now to Fig. 2, the terminals a_1 and b_1 of the repeater U connected to the exchange of the subscriber's device are connected with a_2 and b_2 . A differential relay X, which comprises the single windings X₁ and X₂ and which is bridged-over by a condenser and arranged to be short-circuited by the contact r_1 of the relay R, is connected to the middle of the repeater winding on the subscriber's side in such a way that between the single windings X₁ and X₂ lies the middle-point M₂ which is connected to the negative element of a battery. By the relay contact r_2 the call winding is connected with an audio-frequency generator transmitting the calling sig-

nal, while the winding on the side of the line leads to the line terminals a and b and can be disconnected from the line by the differential relay contact.

5 If it be desired to call up the subscriber, the relay is caused to actuate by non-illustrated means and its contacts r_1 and r_2 are closed. Contact r_1 connects the terminals 3 and 4 of the winding on the side of the subscriber, whereby 10 the differential relay X is neutralised, while contact r_2 connects the call winding of the repeater U with the non-illustrated audio-frequency generator. Owing to the neutralisation of the relay X, its contact x remains in the represented 15 rest position, with the effect that the person calling can, for the sake of control, also hear the calling signal.

When calling up, the position of the contacts SH₁ and SH₂ is that illustrated, while the 20 switches u_1 and u_2 are brought by non-illustrated means into the opposition position (position II) and, likewise in a non-represented manner, an alternating current is connected or superposed to the negative terminal. This alternating current which, on the one side is earthed and, on the other side, connected to the negative terminal, is transmitted through the windings X₁, X₂, the left-hand winding of the repeater U with condenser, the terminals a_1 , a_2 and b_1 , b_2 to the repeater LU which is earthed at M₁. From the repeater LU the calling signal is transmitted 25 through u_1 to the input transformer ET of the amplifier V and through the output transformer AT to the electro-acoustic transformer EW serving as receiver. Therefore, the calling signal is transmitted both to the transformer EW and to the person calling.

At the moment when the person calling breaks 30 the calling signal, the relay R is without current, contacts r_1 and r_2 drop, the differential relay X is no longer short-circuited and the call winding of the repeater is disconnected from the audio-frequency generator. Since X is no longer short-circuited and x_1 and x_2 are no longer connected in 35 parallel, and since, furthermore, SH₂ is still open and keeps the branch M₂— b_1 — b_2 —M₁ without current, contrary to the branch M₂— a_1 — a_2 —M₁, x_1 thus carrying current and x_2 not, X comes into 45 action and its contact x separates the person calling from the repeater. The device thereby locks 50

all incoming calling signals while the open position of SH₁ guarantees that no speaking signals can be transmitted.

To answer the call, the contacts SH₁ and SH₂ are closed and the switches u₁ and u₂ brought into the position shown in the drawing. In this way, the electro-acoustic transformer EW, now working as a transmitter, is connected with a₂—b₂ through u₁, the amplifier V, u₂—SH₁—LU. Since contact SH₂ is closed, the two branches

$$M_2 \left\{ \begin{array}{l} x_1 - a_1 - a_2 - SH_2 - M_1 \\ x_2 - b_1 - b_2 \end{array} \right.$$

connected in parallel and each closed by a winding of the differential relay X (x₁ and x₂) are symmetrical. Relay X remains neutralised and contact x guarantees the transmission of the calling signals transmitted by the transformer EW to the line a—b. When the switches u₁ and u₂ are brought into the other position, the conditions for a communication with the subscriber are fulfilled.

If, on the other hand, the terminals 1 and 2 are short-circuited and the contacts SH₁ and SH₂ open, or if only contact SH₁ is open while contact SH₂ is closed, the device locks all outgoing signals owing to the open contact SH₁, while both the call and the incoming signals are received in EW.

The contacts SH₁ and SH₂ being closed, communications in both directions are possible according to the manner in which the amplifier is connected-in between transformer and repeater by the switches u₁ and u₂.

Therefore, with the device according to the invention it is possible, by merely operating the contacts SH₁ and SH₂ and by a corresponding connection of the switches u₁ and u₂ to obtain a series of speaking, locking and calling possibilities:

Calling: The signal is received in EW without the subscriber having the possibility of transmitting. The person calling can, for control, hear the signal u₁, u₂ in position II, SH₁, SH₂ open.

After the calling, the device locks every signal both the incoming and outgoing ones. To answer the call the switches u₁, u₂ must be in position I and the contacts SH₁, SH₂ closed.

For revertive communication the switches u₁, u₂ must be brought into position II.

When u₁ and u₂ in position II, SH₁ open, SH₂ closed, or, if SH₁ and SH₂ are under the influence of the same operating lever: SH₁ and SH₂ open, terminals 1 and 2 in conductive connection: locking of all outgoing signals, open for all incoming signals.

According to the needs required and in adaptation to the actual local conditions all desirable kinds of transmission can be obtained by simple switching-over.

What I claim is:

1. In an electro-acoustic transmission apparatus, a subscriber's calling device including a subscriber's station, means in said subscriber's station, destined to allow the speaking signals to be locked at will in one or both speaking directions, these means comprising two switches capable of effecting the change in the direction of communication, and two contacts to be controlled by the subscriber.

2. In an electro-acoustic transmission apparatus, a subscriber's calling device including a subscriber's station, means in said subscriber's station, destined to allow the speaking signals to

be locked at will in one or both speaking directions, these means comprising two switches capable of effecting the change in the speaking direction, two contacts to be controlled by the subscriber, and two circuits connected in parallel, in relation with said contacts in order to be made symmetrical or asymmetrical by the influence of one of said contacts.

3. In an electro-acoustic transmission apparatus, 10 a subscriber's calling device including a subscriber's station, means in said subscriber's station, destined to allow the speaking signals to be locked at will in one or both speaking directions, these means comprising, two switches capable of effecting the change in the speaking direction, two contacts to be controlled by the subscriber, two circuits connected in parallel, in relation with said contacts in order to be made symmetrical or asymmetrical by the influence of one 15 of said contacts, lines, switching means destined to switch in and off said lines, said switching means being controllable by the asymmetry of 20 said two circuits connected in parallel.

4. In an electro-acoustic transmission apparatus, 25 a subscriber's calling device including, a subscriber's station, means in said subscriber's station, destined to allow the speaking signals to be locked at will in one or both speaking directions, these means comprising two switches capable of effecting the change in the speaking direction, two contacts to be controlled by the subscriber, two circuits connected in parallel, in relation with said contacts in order to be made symmetrical or asymmetrical by the influence of one 30 of said contacts, lines, a differential relay destined to switch in and off said lines, said differential relay being controllable by the asymmetry of 35 said two circuits connected in parallel.

5. In an electro-acoustic transmission apparatus, 40 a subscriber's calling device including, a subscriber's station, means in said subscriber's station, destined to allow the speaking signals to be locked at will in one or both speaking directions, these means comprising two switches capable of effecting the change in the speaking direction, two contacts to be controlled by the subscriber, two circuits connected in parallel, in relation with said contacts in order to be made symmetrical or asymmetrical by the influence of one 45 of said contacts, lines, a further contact in relation with the call, a part of said parallel circuits being short-circuited by said further contact.

6. In an electro-acoustic transmission apparatus, 50 a subscriber's calling device including a subscriber's station, means in said subscriber's station, destined to allow the speaking signals to be locked at will in one or both speaking directions, these means comprising two switches capable of effecting the change in the speaking direction, two contacts to be controlled by the subscriber, two circuits connected in parallel, in relation with said contacts in order to be made symmetrical or asymmetrical by the influence of one 55 of said contacts, lines, switching means controllable by the asymmetry of said two circuits connected in parallel, and a further contact in relation with the call, a part of said parallel circuits being short circuited by said further contact in such a way that said switching means does, in 60 spite of the existing asymmetry of said two parallel circuits, not come into action.

OTTO TSCHUMI.
